(57) **CLAIM**

The ornamental design for a litter scoop, as shown.

DESCRIPTION

A scoop for the sifting and removal of pet waste, designed for casting from a suitable metal or similar material.

FIG. 1 is a perspective view of a litter scoop showing my new design;

FIG. 2 is a left side elevation view thereof;

FIG. 3 is a right side elevation view thereof;

FIG. 4 is an enlarged front elevation view thereof;

FIG. 5 is an enlarged rear elevation view thereof;

FIG. 6 is a top plan view thereof; and,

FIG. 7 is a bottom plan view thereof.
